(57) **CLAIM**

The ornamental design for a laser beam reflector, as shown and described.

DESCRIPTION

FIG. 1 is a front view of a laser beam reflector of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top plan and left side perspective view thereof;

FIG. 8 is a rear, top plan and right side perspective view thereof;

FIG. 9 is a cross-sectional view along the line 9-9 in FIG. 3; and,

FIG. 10 is a cross-sectional view along the line 10-10 in FIG. 1.
